UNITED STATES PATENT OFFICE.

PAUL SCHURIG, OF BERLIN, GERMANY, ASSIGNOR OF ONE-HALF TO
GUSTAV STEIN, OF SAME PLACE.

CISTERNS FOR WATER-CLOSETS.

SPECIFICATION forming part of Letters Patent No. 678,843, dated July 16, 1901.

Application filed January 8, 1901. Serial No. 42,576. (No model.)

To all whom it may concern:

Be it known that I, PAUL SCHURIG, a subject of the Emperor of Germany, residing at Berlin, Empire of Germany, have invented 5 certain new and useful Improvements in Cisterns for Water-Closets, of which the following is a description.

My invention relates to cisterns for water-closets; and it consists in the arrangement of 10 an air-inlet pipe which normally dips with one end in the water of the cistern and is connected at the other end to the upper part of the main water-float and which is rigidly connected to and supported by a secondary wa- 15 ter-float. This float is arranged in a receptacle provided in the cistern and having a small opening near the bottom, so that the water of the cistern may enter into the said receptacle.

20 One object of my invention is to provide a cistern from which only a predetermined measured quantity of water may flow out irrespective of the water-level in the cistern, which depends, as is well known, on the pressure in the water-conduit.

25 A further object of my invention is to enable the cistern to be entirely emptied, if desired—for instance, for cleaning the closet.

In the accompanying drawings, Figure 1 30 represents a vertical section of the improved cistern, showing the parts at rest. Fig. 2 is a similar section of the cistern, showing the parts after the main water-float has been drawn down, so that the water may flow into 35 the flush-pipe. Fig. 3 represents a vertical section similar to that of Fig. 1, showing the parts in the position which they occupy when the flushing has been stopped automatically. Fig. 4 is a plan view of the apparatus, and 40 Fig. 5 a cross-section on line A B, Fig. 4.

The cistern is filled with water by an inlet-pipe, which is automatically closed by means of a cock controlled in a well-known manner by the rising of the water-level.

45 a is a cistern provided at the bottom with an opening, in which is tightly fixed a receptacle b. The bottom of this receptacle lies below the bottom of the said cistern. The upper part of the receptacle extends into 50 the cistern a and is perforated, so that the

water contained in the latter may enter into the receptacle b.

c is a flush-pipe centrally arranged in the receptacle b and leading to the closet.

d represents the main float, which is guided 55 on the flush-pipe c by means of its tubular guideway f and arranged in a bell e. This bell e is fixed on the float d in such a manner that between it and the outer surface of the float d is left an air-space. The upper part 60 of the bell e is tapered, while the walls at the lower part extend vertically downward and fit loosely in the receptacle b, so that the water from the cistern a may flow between the walls of the bell e and the receptacle b. The 65 lower edge of the bell e is recessed for enabling a free entrance of the water into the interior of the said bell e. The receptacle b as well as the bell e are of elliptic cross-section in order to leave as much room as possible in the cistern a.

Above the guideway f of the float d is secured to the bell e an elbow-pipe g, the free end of which is connected by a flexible tube h with the pipe i. The latter is fixed to a 75 support carried by a perforated pipe k and dips normally into the water of the cistern a, so that a water seal is obtained which prevents the air from entering into the pipe i. l is a secondary float secured to the lower end 80 of said pipe k and adapted to move up and down within a receptacle m. This receptacle m is arranged in the cistern a and is provided near the bottom with a small opening n, so that the water of the cistern a may enter 85 the receptacle m.

The float l is guided by a pipe o, extending upward from the bottom of the receptacle m and having its upper end above the water-level, so that the water may not enter into 90 the same. To the upper closed end of the pipe k is fixed a chain p or the like, which extends downwardly through the pipes k and o and may be fixed within the reach of an attendant. When the water flows into the cistern a, the main float d and the secondary float l will rise until the water-inlet pipe is closed, at which moment the floats will be in the positions shown in Fig. 1. The water within the space between the bell e and the 95 100

float *d* will be at about the same level as in the cistern *a* and the receptacle *m*. If the float *d* is depressed by means of chains *z* or the like, fixed in any convenient manner to the upper end of the bell *e*, the water below the latter will be forced upward and flow down into the guideway *f* and flush-pipe *c*, whereby a suction will take place in guideway *f*. (See Fig. 2.) By this suction the water from the cistern *a* is drawn through the holes of the receptacle *b* into the latter and entering the bell *e* flows over the upper end of the float *d* into the flush-pipe *c*. This flowing is interrupted as soon as the water-level in cistern *a* has sunk below the lower end of the pipe *i*, Fig. 3, which will take place at a certain predetermined moment, because the water in the receptacle *m* cannot flow out through the hole *n* into the cistern so quickly as it flows out through the pipe *c*. Thus the float *l* will not sink so quickly as the water-level in cistern *a*, owing to the fact that the water-level in the cistern *a* has sunk more quickly than in *m*, and consequently the float *l* retains the end of the pipe *i* above the water-level in cistern *a*, allowing air to enter the said pipe, and when the pipe *i* reaches the position shown in Fig. 3 air may enter the same and will pass by suction through the tube *h* and pipe *g* into the interior of the bell *e*. By means of this the outflow of the water is interrupted. Since now no further suction can take place in *f*, the water will lift the float *d* to the position Fig. 3. While the level of water is sinking the water-inlet pipe is opened in the well-known manner and the cistern *a* will be filled again, whereby the floats *d* and *l* regain their normal position, Fig. 1.

If a greater quantity than the ordinary quantity for flushing should be used which may be necessary for cleaning the closet, the attendant after having depressed the bell *e* will pull the float *l* downward by means of chain *p*, so that the lower end of the pipe *i* will nearly reach the bottom of the cistern *a*. It is therefore evident that the water will then flow out until the level has sunk beneath the end of this pipe, so that the basin will be practically emptied.

Since no levers are necessary in connection with my improved cistern, I am enabled to make all parts of zinc or tinned copper, thus preventing the formation of rust. It is obvious that I could connect the chains or the like, by means of which the bell *e* is depressed, to the movable seat of the water-closet, so that the flushing will be automatically effected, without departing from my invention.

I claim as my invention—

1. In combination with a cistern for water-closets, a bell dipping into the water in the cistern, a float connected with the bell, means

for depressing the bell to discharge the water from the cistern, a movable air-pipe dipping 65 into the cistern-water, a connection between the said air-pipe and the bell whereby the said bell will be supplied with air from said air-pipe when the cistern-water falls below the end of the said air-pipe, a float connected with 70 the air-pipe and a receptacle for containing water and having a small outlet which will cause the water-level in said receptacle to fall slowly as compared with the fall of water in the cistern, substantially as described. 75

2. In combination with a cistern for water-closets, a bell dipping into the water in the cistern, a float connected with the bell, means for depressing the bell to discharge the water from the cistern, a movable air-pipe dipping 80 into the cistern-water, a connection between the said air-pipe and the bell whereby the said bell will be supplied with air from said air-pipe when the cistern-water falls below the end of the said air-pipe, a float connected with 85 the air-pipe and a receptacle for containing water and having a small outlet which will cause the water-level in said receptacle to fall slowly as compared with the fall of water in the cistern, the said connection between 90 the air-pipe and bell being a flexible one whereby the bell may fall at a greater speed than the air-pipe and the outlet from said receptacle leading into the cistern, substantially as described. 95

3. In combination with a cistern for water-closets an air-inlet pipe the lower end of which dips normally into the water of a cistern, a bell supported by a main float, pipe connection between that bell and pipe, a secondary 100 float rigidly secured to the latter, a receptacle within the cistern having a small opening near the bottom, and adapted to guide the said secondary float, and means by which the latter may be depressed, substantially as described. 105

4. In combination with a cistern for water-closets an air-inlet pipe, the lower end of which dips normally into the water of a cistern, a bell supported by a main float, a space between the outer wall of the latter and the bell, a pipe secured to the upper end of the bell and connected with the said air-inlet pipe, means for depressing the bell, a secondary 110 float rigidly secured to said air-inlet pipe 115 a receptacle within the system having a small opening near the bottom and adapted to guide the said secondary float and means by which the latter may be depressed, substantially as described. 120

In witness whereof I have hereunto set my hand in presence of two witnesses.

PAUL SCHURIG.
